BY Higdon Young, Atty.

UNITED STATES PATENT OFFICE.

NATHAN J. GOODMAN, OF ST. LOUIS, MISSOURI, ASSIGNOR TO SIMPLEX SELF HOLDING CARTON COMPANY, OF ST. LOUIS, MISSOURI, A CORPORATION OF MISSOURI.

CARTON.

No. 924,761.

Specification of Letters Patent. Patented June 15, 1909.

Application filed March 28, 1908. Serial No. 423,959.

To all whom it may concern:

Be it known that I, NATHAN J. GOODMAN, a citizen of the United States, and resident of St. Louis, Missouri, have invented certain new and useful Improvements in Cartons, of which the following is a specification containing a full, clear, and exact description, reference being had to the accompanying drawings, forming a part hereof.

10 My invention relates to a carton or holder, particularly adapted for holding laundered shirts, vests, waists, and the like, and the object of my invention is to provide a simple and inexpensive carton or holder which may 15 be readily folded for use, and which will maintain the contained article in a neat and convenient manner without the use of pins or strings, or like fastening devices.

To the above purposes, my invention consists in certain novel features of construction and arrangement of parts, which will be hereinafter more fully set forth, pointed out in the claim, and illustrated in the accompanying drawings, in which:

25 Figure 1 is a plan view of a carton of my improved construction, the same being open; Fig. 2 is an elevation of a carton folded for use, and inclosing a shirt; Fig. 3 is an enlarged detail section taken on the line 3—3 30 of Fig. 2; and Fig. 4 is a plan view of a modified form of the carton.

Referring by numerals to the accompanying drawings: 1 designates the base or back of the carton, which is preferably constructed 35 of cardboard or analogous material, and of such size as to readily accommodate a shirt or like article of wearing apparel when the same is properly folded after being laundered.

Secured to the sides of the base or back 40 are flexible sections 2, of light strong paper or analogous material, which sections 2 are of such width as that when folded over onto the front of the base 1 their edges overlap. The outer corners at the top of these sections 45 2 are cut away, as designated by 3, in order to accommodate the neck band of a shirt when the same is positioned in the carton.

Secured in any suitable manner to the lower end of the base 1 is a rectangular section 4, of flexible material, such as paper, said section being preferably of the same width as is the base 1, and secured in any suitable manner to the lower end of said sec-

tion 4 is a transversely disposed strip 5 of thin, ductile metal, such as tin. 55

In the use of a carton of my improved construction, the shirt, properly folded, is laid upon the base 1 with the neck band at the top thereof, after which the sections 2 are folded over onto the bosom of the shirt, and when so arranged the neck band projects through the semicircular opening formed by the cut away corners of the sections 2, and the section 4 is now folded over onto the lower portions of the sections 2, and the projecting ends of the strip 5 are now bent downward and into position immediately beneath the side edges of the base 1, thus uniting the sections 2 and 4 with the base, and clamping the shirt or like article between the sections 2 and said base. The shirt thus enclosed is held in a neat and convenient manner, and cannot become soiled as a result of handling during delivery. 65 70 75

In the modified form of the carton shown in Fig. 4, a rectangular flexible section 6 is attached to the top of the base 1, which section 6 is folded over onto the upper portions of the sections 2 when the carton is in use, thus forming a complete envelop for waists, vests, collars and cuffs, or like articles of merchandise. 80 85

Cartons of my improved construction are particularly applicable for inclosing laundered articles, although they may be advantageously used for holding articles of wearing apparel and the like which are displayed for sale and which are to be delivered to the customer in a neat and clean condition. 90

I claim:

A carton comprising a stiff base, a pair of flexible sections secured at their edges to opposite sides thereof, the upper outer corners of which flexible sections are cut away, a flexible section secured to the lower end of the base, and a ductile strip arranged on the lower end of the last mentioned flexible section. 95

In testimony whereof, I have signed my name to this specification, in presence of two 100 subscribing witnesses.

NATHAN J. GOODMAN.

Witnesses:

M. P. SMITH,
E. L. WALLACE.
